US00D930963S

(12) **United States Design Patent** (10) Patent No.: **US D930,963 S**
(45) Date of Patent: **** Sep. 21, 2021**

- (54) **SHOE**
(71) Applicant: **adidas AG**, Herzogenaurach (DE)
(72) Inventor: **Gregor McWee**, Portland, OR (US)
(73) Assignee: **adidas AG**, Herzogenaurach (DE)
(**) Term: **15 Years**
(21) Appl. No.: **29/703,992**
(22) Filed: **Aug. 30, 2019**

Related U.S. Application Data

- (63) Continuation of application No. 29/632,662, filed on Jan. 9, 2018, now Pat. No. Des. 863,743.

(57) **CLAIM**

The ornamental design for a shoe, as shown and described.

DESCRIPTION

FIG. 1 is a bottom perspective view of a shoe showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the shoe that form no part of the claimed design.

1 Claim, 6 Drawing Sheets
